LOUIS FRIEDMANN AND HANS DEUTSCH, OF VIENNA, AUSTRIA, ASSIGNEES TO THE
FIRM ALEX FRIEDMANN, OF VIENNA, AUSTRIA

FEEDING DEVICE FOR THE BOILERS OF LOCOMOTIVES

Application filed February 28, 1929, Serial No. 343,416, and in Austria March 7, 1928.

Our invention relates to a boiler feeding device for locomotives of the type comprising a hot water tank or container to be filled with water which may be set into communication with the steam space of the boiler, whereby the water in the tank or container may be emptied into the boiler under the pressure of the live steam of the boiler.

According to our invention and in contradistinction to similar arrangements hitherto known said tank or container is filled with water by means of an injector operating with live steam and with exhaust steam: the live steam of boiler pressure within the container being fed to the live steam nozzle of the injector as long as such live steam is still present while the exhaust steam flowing from the exhaust steam pipe of the locomotive will be led to the exhaust steam nozzle of the injector. When the supply of live steam within the hot water tank or container is exhausted the injector will continue to work with exhaust steam alone and this is possible without difficulty on account of the fact that during the decrease and final exhaustion of the live steam supply within said tank or container also the counterpressure within the container will decrease and finally be reduced to substantially atmospheric pressure.

The hot water tank or container may be arranged above the water level of the boiler so that after the admission of live steam of boiler pressure to said container by opening a suitable shutting off member the water may gravitate into the boiler. But the hot water tank or container may also be arranged at a lower level than the water level of the boiler and in this case of course even after admitting live steam of boiler pressure the water from the container will not flow of its own accord into the boiler. In this case according to our invention a special delivering or feeding means, for instance, a pump is arranged capable of delivering the hot water supply within the container into the boiler in spite of the difference of level between the container and the boiler.

The invention is illustrated in the accompanying drawing in which Fig. 1 shows a locomotive provided with the arrangement de-

scribed in which the container is located at a higher level than the water level of the boiler. Fig. 2 shows another modification in which the container is arranged at a lower level than the water level of the boiler. Fig. 3 finally shows an exhaust steam injector such as used for feeding the container.

In Fig. 1 the reference numeral 1 designates a hot water tank or container of the usual type within which hot water may be accumulated or heated, in order to be able to feed the boiler with water of relatively high temperature. Said hot water tank or container may be set into communication with the steam space of the boiler by means of the piping 2, a valve 3 being inserted in said piping in order to be able to shut off the communication between the container and the boiler. A further piping 4 leads from the lower part of the container into the boiler, through which the contents of the hot water container may be discharged and a non-return valve 5 is inserted in this piping. A live steam piping 6 is arranged leading from the injector to the container 1, said live steam piping being controlled by a valve 7. The injector is moreover in communication with an exhaust steam pipe 8 leading from the blast or exhaust pipe of the locomotive to the injector and with a delivery pipe leading from the pressure or delivery space of the injector to the container. The injector is moreover provided with a water piping 10, with a live steam nozzle 11, and with an exhaust steam nozzle 12.

The hot water tank or container 1 can only be fed with water heated by exhaust steam during that period of time within which the locomotive is running with open regulator so that exhaust steam is available.

The operation of the arrangement is the following:

If the hot water tank or container has to be supplied with water during or immediately after the feeding of hot water from the container into the boiler such feeding has to occur against a counterpressure which is approximately equal to the pressure within the boiler and which in any case is so high that feeding of water with exhaust steam alone

by means of the injector is not possible. Now when the valve 7 in the pipe 6 is opened live steam will flow from the container to the live steam nozzle as long as a supply of live steam is still present within the container. 5 This current of live steam through the live steam nozzle now allows in cooperation with the exhaust steam flowing through the exhaust steam nozzle 8 the feeding of water to 10 the container. As, however, the injector does not need any additional live steam supply through the piping 6 any longer than the presence of a high steam pressure in the container will necessitate it, the arrangement described will allow a feeding of water into 15 the container quite independently from the pressure within the same and it is also obvious that the steam that has been admitted to the container is thus utilized for feeding 20 purposes.

In the arrangement shown in Fig. 2, 1 again designates the hot water tank or container, 2 the exhaust steam injector; 13 denotes a hot water pump which is driven by a 25 steam motor 14 and which exercises a sucking action by means of the pipe 15 in the hot water container 1. Said pump will lift the hot water by means of the pipe 16 from the container and press it into the boiler.

30 The pipe 17 will carry the exhaust steam from the working cylinder of the locomotive to the exhaust steam injector 2. Said exhaust steam injector will draw in water from the tender through the pipe 18 and after having mixed it with the exhaust steam will 35 press it into the pipe 19 and into the container 1. Said container 1 is also connected by means of a pipe 21 provided with a shutting off valve 20 with the live steam nozzle 40 11 of the exhaust steam injector 2.

Moreover a pipe 22 leads from the container 1 over a shutting off member 23 to the steam space or dome of the boiler. When the 45 valve 23 is opened the container 1 will be under boiler pressure. The steam motor 14 which drives the hot water pump 13 will operate as it is supplied with steam by means of the pipe 24 which branches off from the pipe 22. The exhaust steam from the small 50 steam motor 14 may be led into the water container of the tender in order that it may not be lost, as shown in Fig. 2, and a pipe 55 is arranged for this purpose.

55 The operation of this arrangement is the following:

When the locomotive is running with an open regulator the exhaust steam of the locomotive will flow through the pipe 17 to the 60 exhaust steam injector 2 and will carry water from the tender into the hot water container 1 by means of the pipe 19, said water being mixed with the exhaust steam and being thereby heated. At this moment 65 substantially atmospheric pressure will pre-

vail within the water container 1. The valve 23 is closed at present. When the container 1 has been filled with hot water and if it is now necessary to feed the boiler first the valve 20 is closed and the valve 23 is opened. 70 Thereby steam of boiler pressure is admitted to the container. The steam motor 14 is now driving the hot water pump 13 and hot water is fed from the container 1 into the boiler of the locomotive. 75

When the hot water supply within the container 1 is exhausted the whole volume of the hot water container 1 is filled with steam having the same pressure as the steam within the boiler. Now the valve 23 is again 80 closed and the valve 20 is opened. The steam within the container 1 which is of the same pressure as that prevailing in the boiler is now flowing through the pipe 21 to the live steam nozzle of the exhaust steam injector 85 2 and water from the tender is fed into the container. Said live steam therefore will co-operate with the exhaust steam to feed the water into the container until the steam supply within the hot water container has 90 been entirely consumed. When the hot water container has again become pressureless the exhaust steam will again operate alone to fill the container.

95 From the above it will also be seen that with heating arrangements having a hot water container arranged at a lower level than the water level of the boiler it is possible to utilize the quantity of live steam which has been introduced into the container and which is lost in other arrangements, provided that an exhaust steam injector forms the feeding device for the cold water.

Moreover a hot water feeding device must be provided which feeds the hot water from 105 the container under boiler pressure into the boiler and which is capable to overcome the difference of level between the container and the water level within the boiler.

110 What we claim is:—
A locomotive feed water heating arrangement comprising a hot water storage tank having its lowermost portion located above the high water level of the boiler; a connection from said lowermost portion to the boiler check valve; a valved pipe connecting the steam space of the boiler with the uppermost portion of the storage tank; an injector having a cold water inlet and a hot water outlet, 115 an exhaust steam nozzle, and a live steam nozzle, the construction and arrangement of the injector being such that it will operate with exhaust steam alone or with exhaust steam and live steam simultaneously; a pipe 120 connecting an exhaust port of the engine and the exhaust nozzle of the injector; a valved pipe connecting the uppermost portion of the storage tank and the live steam nozzle of the injector, a pipe connecting the 125 130

said hot water outlet and the hot water storage tank, and a check valve in said last mentioned pipe opening in the direction of the hot water storage tank.

5 In testimony whereof they affix their signatures.
